UNITED STATES PATENT OFFICE.

ISIDOR KITSEE, OF PHILADELPHIA, PENNSYLVANIA.

ELECTRIC TELEGRAPHY.

No. 820,977.

Specification of Letters Patent.

Patented May 22, 1906.

Application filed June 10, 1905. Serial No. 284,657.

To all whom it may concern:

Be it known that I, ISIDOR KITSEE, of the city and county of Philadelphia and State of Pennsylvania, have invented certain new and useful Improvements in Electric Telegraphy, of which the following is a specification.

My invention relates to an improvement in telegraphy, and has more special reference to the receiving of telegraphic intelligence on submarine or long-distance lines.

In Letters Patent No. 777,259, dated December 13, 1904, I have described a method of telegraphing over submarine or long-distance lines with the aid of true reversals.

This my invention has special reference to the receiving of such true reversals even over long-distance submarine; and it is the object of my invention to receive such true reversals over long-distance cables in a manner so that the same may be recorded in accordance with the Morse method of recording or may be relayed to a second cable or to land-lines.

In the accompanying drawing, which is a diagrammatic view showing the devices employed, I have shown a polarized relay as the receiving device and a Morse embosser as the recording device; but it is obvious that instead of the Morse embosser other instruments may be substituted.

In this figure, A is a polarized relay sensitive enough for the purpose required. I may use the well-known Siemens' polarized relay, which is preferably wound so as to have a resistance of about four thousand ohms; and in this drawing I have illustrated parts of this relay, so as to enable persons versed in the art to use the same in accordance with my invention, and I have designated the polarized armature as C, the two electromagnets as B and B', and the two contact-points as D' and D''. The binding-posts for the two coils are designated as 4 and 6, and the binding-post for the connection to the armature as 5. So far the arrangement of the relay is substantially the usual one, and as the Siemens' polarized relay is well known it is unnecessary for me to go more into the detail of the construction and arrangement of same.

As is usual, the binding-post 6 is connected with the line and the binding-post 4 with the ground Z. I have not illustrated the different devices to be placed, specially in submarine telegraphy, in the line or between the ground and the relay, as such devices do not form part of my invention.

Instead of the usual connection of the binding-posts D' and D'', each to a separate circuit, I have connected both of these binding-posts to an additional binding-post, (designated as 3.) These binding-posts D' and D'' are therefore always in electrical connection with each other and with the binding-post 3.

1 is a source of current forming a circuit embracing the electromagnet F, the resistance F', and the switch f. The electromagnet F is provided with the armature G', held upward by the spring g. g' and g'' are two adjustable contacts in proximity to this armature. The resistance F' has to be of a value high enough to prevent the current of the source 1 from energizing the magnet F. Normally, therefore—that is, when the switch f is closed—the energizing effect of 1 will not be sufficient to draw the armature G' toward the stop g'', and this armature will always remain in contact with g', and to actuate this armature it is necessary to either decrease or shunt the resistance F', placed in its circuit, and for the purpose of making active this armature through the relay A, I have recourse to the following arrangement:

I connect the contact 3, through wire 7, with the leg 9 of the circuit just described, and I connect the binding-post or contact 5, through wire 8, with the leg 10 of the circuit just described. When, therefore, the armature C, in electrical contact with point 5, touches one or the other of the contacts D' and D'', in electrical connection with point 3, then a circuit is established shunting the resistance F', and as the resistance value of the shunt is far less than the resistance value of F' and as the current from 1 is sufficient to energize the electromagnet F, provided no other resistance is present in the circuit, it is obvious that as soon as the shunt is established the current-flow from 1 will energize the electromagnet F to a degree so as to pull the armature G' downward and in contact with the adjustable point g''. In the drawing I have illustrated a second local circuit as to embrace the source of current 2, the annunciating device H, the electromagnet I, adapted to be used as a sounder or relay, and the recording device K. I have also illustrated this circuit as to contain the switches f' and f'' for the reason as will hereinafter be described.

The arrangement of the relay A is such that the tongue or armature C always rests against one or the other of the contacts D'

or D^2 . It is supposed that the polarity of the coils is such that the negative impulse will send the armature C toward and in contact with D' and that the positive impulse 5 will send the armature C toward and in contact with D^2 , and it is supposed that the last impulse transmitted was a negative one and that therefore, as is illustrated in the drawing, the armature rests at D' . If now the 10 operator wishes to transmit true reversals, he actuates his transmitting means in a manner so that positive or negative impulses will be sent over the line. Each impulse will actuate the relay in a manner so that the armature 15 will move from one contact to the other. During this period—that is, during the time that the armature moves from one contact to the second contact—the shunt around the resistance F' will be open, and the armature 20 G' will be drawn toward and in contact with the point g' , thereby closing an electric circuit, including the necessary translating devices, such as for distance, as are illustrated in the drawing.

25 In Letters Patent above referred to I have described a system whereby one character of the Morse alphabet—say the dot—is characterized by one impulse, the polarity not coming into consideration, and the second character—say the dash—is characterized by two impulses in quick succession, these two impulses of opposite polarity to each other.

The translating device in the circuit containing the source 2 will therefore be actuated in accordance with the difference of time lapsing between the different impulses. It is supposed that the operator wants to 35 transmit a dot. He presses the transmitting key once, and the translating device in the circuit containing the source 2 will answer to this one impulse during the time that the armature C travels from one contact to the other. Should the operator now desire to transmit a dash, he presses the key twice in 40 quick succession, which results in transmitting two impulses in quick succession, the armature will therefore travel from one contact to the other and then from the second contact back to the first. This will release 45 the shunt around F' twice in quick succession and the translating device in the circuit will answer twice in quick succession, and the receiving operator being aware that two impulses in quick succession symbolize a dash 50 will be able to translate the message, provided the same consists of dots and dashes symbolized as aforesaid. It will therefore be seen that in contradistinction to the re-laying arrangement as employed to-day I do 55 not actuate the translating device through the making of the contact; but I actuate the translating device through the breaking of the contact of the receiving device.

I have not placed the necessary translating device in the first local circuit for the rea-

son that a sensitive device such as has to be employed on long lines or cables cannot well be made to change the resistance of the circuit sufficiently if such circuit contains high electromotive force, which is necessary for the actuating of translating devices, and I therefore have substituted the intermediate circuit containing the source 1, and in practice I use in this intermediate circuit one dry cell, a relay of twenty-five ohms, and a resistance of about fifty ohms, the relay answering satisfactorily when the resistance was shunted, but remaining unaffected as long as the shunt was broken.

I have stated above that the Siemen's relay substantially as is made to-day may be employed; but in the actual employment I had recourse to some changes which I have found to be advantageous; but as these changes will form the subject-matter of another application it is unnecessary to give the same in detail here.

Having now described my invention, what I claim as new, and desire to secure by Letters Patent, is—

1. In telegraphy, a line of transmission, a polarized relay connected to said line of transmission, contacts for said polarized relay, said contacts in electrical connection with each other and with one terminal of a local circuit, the other terminal connected to the armature of said relay, a local circuit containing translating devices, a source of current and a resistance, said resistance adapted to be shunted through the contacting of said armature with one or the other of said contacts.

2. In telegraphy, in combination with a line of transmission, a receiving device consisting of a polarized relay provided with contacts, a closed local circuit embracing a source of current, an electromagnet and a resistance of a value great enough to normally make said electromagnet inoperative; a shunt around said resistance, one terminal of said shunt in electrical contact with the movable part of said relay and the second of said terminals in electrical connection with the contact of said relay, and means at said relay to shunt through said movable part said resistance, thereby making operative said electromagnet.

3. In telegraphy, a receiving device comprising a polarized relay connected to the line and ground respectively, a normally closed local circuit comprising an electromagnet, a source of current, and a resistance, in combination with a shunt around said resistance and means at said relay to open and close said shunt.

4. In telegraphy, a closed local circuit, a translating device connected in said circuit but non-operative by the normal current strength therein, a non-inductive resistance also connected in said local circuit, a main

line, and a receiving instrument connected to be operated by current in said main line to shunt said resistance for the operation of said translating device.

5. A telegraph-line having a main-line relay connected therein, a closed local circuit, a non-inductive resistance included in said local circuit, said resistance being controlled by said relay, and a translating device operated by current in said closed circuit.

6. A telegraph-line having a main-line relay connected therein to be operated by cur-

rent passing over said line, a non-inductive resistance connected in series with the tongue and forward contact of said relay, a closed circuit, and a translating device connected to be operated by current in said closed circuit.

In testimony whereof I hereby sign my name, in the presence of two subscribing witnesses, this 8th day of June, A. D. 1905.
